(57) **CLAIM**

The ornamental design for a printer with copying, scanning and facsimile functions, as shown and described.

DESCRIPTION

FIG. 1 is a perspective view of a printer with copying, scanning and facsimile functions with the lid in a closed position;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is another rear perspective view thereof with the lid in an open position.

The rear view contains no ornamentality and is omitted.

The broken lines are for purposes of illustration only and form no part of the claimed design.
